E. G. HEDGES

CLOSET FLUSHING VALVE

Filed Sept. 22, 1922

Inventor.

Edward G. Hedges, Jr.
Thomas S. Crane, Atty.

UNITED STATES PATENT OFFICE.

EDWARD G. HEDGES, OF NEWARK, NEW JERSEY.

CLOSET-FLUSHING VALVE.

Application filed September 22, 1922. Serial No. 589,953.

To all whom it may concern:

Be it known that I, EDWARD G. HEDGES, a citizen of the United States, residing at Newark, county of Essex, and State of New Jersey, have invented certain new and useful Improvements in Closet-Flushing Valves, fully described and represented in the following specification and the accompanying drawings, forming a part of the same.

10 The object of the present invention is to improve the construction of a flush-valve so as to increase its efficiency, so as to automatically discharge air which enters the flushing-chamber, so as to obviate vibration and hammering, and so as to facilitate the adjustment or regulation of the flush-valve, and produce a greater or less flushing of the fixture to which the valve is attached.

15 The invention includes a special arrangement of the bleeding-hole or equalizing port which extends through the diaphragm, and means to retain it in a preferred position to secure the automatic cleansing of such port at each actuation of the valve.

20 It also includes the extension of an air-shifter-pipe from the relief-valve to the upper part of the compression chamber, so that any air in the upper part of the compression-chamber is automatically discharged at each flushing movement. It also includes the attachment to the flushing-spindle, of a sleeve-valve which, when the pull-handle is operated, presses upon the diaphragm and cuts off the escape of any fluid from the 25 supply-chamber, except through the relief-valve.

It also includes other details of construction.

25 The annexed drawing shows in Fig. 1 a longitudinal central section of the flush-valve with its various attachments; Fig. 2 is an elevation of the relief-valve-box with the air-snifter-pipe attached; Fig. 3 is an elevation of the diaphragm showing the relief-valve fixture thereon with its square valve-stem; and Fig. 4 is an enlarged sectional view of the diaphragm and its attachment with the relief-valve opened. Fig. 1 shows the compression-chamber full, and Fig. 4 shows it empty. 4 designates the supply-chamber; 5 the compression-chamber; 6 the discharge-chamber; 7 the seat for the diaphragm; 8 the diaphragm; 9 the pull-handle; 10 the spindle moved by the pull-handle; 11 the relief-valve-stem; 12 the re-

lief-valve; 13 the relief-valve-box; 14 the equalizing port; 15 the air-snifter-pipe; 16 the hub of the diaphragm; and 17 the recess for the relief-valve-box in the outer side of the compression-chamber. A spiral-spring 60 18 is fitted in the relief-valve-box to hold the relief-valve normally closed, thus preventing any escape of water by the air-pipe. The relief-valve-box is attached to the diaphragm and has a relief-valve-seat 21 integral with 65 a hollow threaded projection 26 extending through the diaphragm.

In other flush-valves the equalizing port is drilled in the metal of the compression-chamber, but in this invention is extended 70 through the diaphragm so as to form a short and straight passage between the supply and compression-chambers, which conduces to a constant clearing of the passage, thus maintaining a reliable and uniform operation of 75 the flush-valve.

In the present invention this equalizing port is preferably located near the upper edge of the diaphragm close to the supply-chamber, so that every time the valve is 80 flushed the fluid passing from the supply-chamber into the bore of the seat 7 washes off the end of the port and keeps the port constantly open. The port thus operates reliably in regulating the filling of the compression-chamber, which ultimately closes 85 the channel around the inner end of the seat 7 at the close of the flushing operation.

The relief-valve-box is clamped upon the center of the diaphragm by hub 16, and the 90 relief-valve-stem 11 projects through the hub in line with the spindle 10. The stem is made square to form passages 20 through the hub.

The relief-valve is of piston-shape and is 95 held by the spring 18 in a position to normally close the passages 20.

The piston fits the box loosely so as not to choke the outlet of the air-pipe, which extends into the side of the valve-box. A 100 sleeve-valve 19 is shown in Fig. 1 attached to the spindle 10, and is fitted movably to the bore of the diaphragm-seat.

The actuation of the pull-handle forces the sleeve toward the diaphragm as shown in 105 Fig. 4, and thus prevents the valve temporarily from flushing, as it closes the channel 21, between the diaphragm and its seat 7. The release of the handle draws back the 110 sleeve-valve and causes the flush to follow.

Fig. 4 shows these features clearly by its exaggerated proportions.

When the relief-valve is pushed from its seat by the spindle 10 the water in the compression-chamber is vented by passing gradually through the hub-passages 20 into the chamber 6. At the same time the first discharge of water through the air-pipe carries with it any air accumulated in the upper 10 part of the compression-chamber.

The air-sniffer-pipe 15 extends upward from the relief-valve-box 13 to the upper part of the compression-chamber.

The supply-chamber 4 is supplied with 15 water under pressure, and the discharge-chamber 6 is empty until the pull-handle is operated to produce the flushing movement.

Under these conditions the equalizing port permits the fluid from the supply-chamber to gradually fill the compression-chamber under the same pressure as the source of supply. The actuation of the pull-handle pushes the relief-valve from its seat, thus forming a communication between the top- 20 end of the air-pipe and the passages around the stem of the relief-valve. This outlet reduces the pressure in the compression-chamber, and the super-pressure of the fluid in the supply-chamber pushes the dia- 25 phragm from its seat and permits the water in the supply-chamber to escape into the discharge-chamber through the channel 21 between the diaphragm and its seat 7, as shown by the arrows 7' in Fig. 4.

30 The actuation of the pull-handle not only lifts the relief-valve from its seat to initiate the flushing, but the spindle 10 presses upon the stem 11, as shown in Fig. 4, and pushes the diaphragm from its support or seat 7, 40 (see Fig. 4) thus positively opening the dia- phragm for a quick and effective flushing movement.

The degree to which the spindle 10 pushes 45 open the diaphragm is regulated by a screw 25 seated in the recess 17 in the casing 17' around the valve-box. A cap 26 is screwed in the casing over the outer end of the screw 25, which end is notched to admit a screw-driver by which the screw can be 50 set near to or farther from the relief-valve-box, and thus determine the rapidity of discharge to the discharge-chamber. Such screw can be adjusted while the flush-valve is in its operating position.

55 It will be understood that the seat 7 projects from the upper part of the discharge-chamber toward the compression-chamber, and is surrounded upon its outer sides with water under pressure in the chamber 4.

60 It will be observed that the compression-chamber is completely cut off from the supply-chamber except by the equalizing port 14, and that the diaphragm can only be pushed into the compression-chamber by 65 pushing fluid out through the relief valve.

This fluid when the flushing is completed is replaced through the equalizing port.

The filling of the compression-chamber finally brings the diaphragm against its seat 7, as shown in Fig. 1, which stops the flow 70 of water from the supply-chamber to the discharge-chamber.

Several defects in such flush-valves are corrected in the present construction. In many previous constructions the equalizing port is located where the sediment in the water is liable to clog the necessarily small 75 passage which forms this port.

The accumulation of air, which is one of the greatest defects in ordinary flush-valves, is prevented in the present construction, by 80 extending a so-called air-sniffer-pipe 15 from the relief-valve-box to the upper part of the compression-chamber, so that any air which is trapped in the compression-chamber is discharged at the first actuation of the flush-valve into the relief-valve-box, and thence through the passage or passages 85 around the valve-stem.

The rapidity of the water's movement 90 through a flush-valve is affected by the pressure of the supply-fluid, and the present invention furnishes a means of regulating the degree in which the channel 21 for the fluid is opened when the pull-handle is actuated so that the valve may be used with 95 any pressure in the supply-chamber.

Such regulating is effected by the screw 25 which opposes the movement of the dia- 100 phragm and thus determines the extent to which the diaphragm can be pushed out- ward with the relief-valve-box. Such regu- lation determines the clearance between the seat 7 and the diaphragm, where the ar- 105 rows 7' are shown in Fig. 4. The larger the clearance that is permitted at this point by the adjustment of the screw 25 the greater volume of water discharged at each 110 actuation of the flush-valve. This increases the time of the flushing until the compres- sion-chamber is refilled through the equalizing port. Leakage often occurs at the stuff- 115 ing-box of the valve-spindle 10 by the wear of the ordinary packing, and such leak- age is prevented in the present construc- 120 tion by providing the stuffing-box 22 with a washer 23 upon the outer side of the pack- 125 ing 24 and clamping a spiral-spring 25 within the stuffing-box 22 to keep the washer pressed elastically upon the packing.

Such spring-washer operates to compensate for the wear of the packing, by crowd- 130 ing the same constantly upon the bottom of the stuffing-box, which is tapered as usual.

If desired, the spindle 11 may have a sleeve-valve attached to it within the seat 7 to contact with the diaphragm, but the other parts operate equally well without the sleeve-valve.

The compression-chamber is formed in an 130

auxiliary casing 27 screwed upon the outer side of the supply-chamber, and means is provided within the compression-chamber to locate the air-sniffer-pipe so that it extends from the relief-valve-box into the top of the compression-chamber.

Such means is requisite because the casting of the compression-chamber is necessarily made removable to introduce the dia-

10 phragm and clamp it in position.

The air-pipe is a part of the relief-valve-box, which is attached to the diaphragm, and is liable in assembling the parts to be turned in some other direction than toward 15 the top of the compression-chamber, where it would secure the positive discharge of any air that accumulated in the chamber. Means for properly positioning the air-pipe as shown in Fig. 2 may consist of two lugs 20 28 within the top of the compression-chamber which lugs locate the top of the air-pipe and hold the air-pipe in such position during the screwing of the auxiliary casing 27 upon the main casing 27'. Any other suitable 25 means may be used to thus locate the air-pipe.

The drawing shows details of construction by which the parts are fitted and held together; but it is immaterial what constructive features are employed to embody the essential elements which are pointed out in the claims.

When the flush-valve is operating all the fluid vented from the supply-chamber passes 35 between the end of the sleeve-valve and the diaphragm, as shown by the arrow 7' in Fig. 4; but the connection of the sleeve-valve 19 with the valve-spindle 10 is capable of arresting the current through the flush- 40 valve at any moment, when from any cause it is undesirable to permit the completion of the flushing operation.

Such arrest of the flushing is controlled by pressing the pull-handle until the sleeve- 45 valve contacts with the diaphragm; this prevents any passage of fluid from the supply-chamber to the discharge-chamber through the interior of the sleeve-valve. This construction therefore places the operation of 50 flushing entirely under the control of the operator.

Having thus set forth the nature of the invention what is claimed herein is:

1. A flush-valve comprising a supply 55 chamber having an inlet opening, a discharge chamber, a compression chamber, an annular valve seat, a valve normally resting upon said seat and disposed between said compression chamber and said discharge 60 chamber, and an equalizing port comprising a direct passage extended through said valve, said port being disposed externally to said valve seat and adjacent said inlet opening and so arranged with respect to the inlet 65 opening that it is in the direct path of flow

of fluid passing through said valve during a flushing action.

2. A flush-valve comprising a supply chamber having an inlet opening, a discharge chamber, a compression chamber, an 70 annular valve seat, a valve normally engaging said seat and separating said discharge and compression chambers, and an equalizing port in said valve and having an aperture therethrough, said port being disposed externally of said annular valve seat and so arranged with respect to the inlet opening as to be in the path of flow of fluid through said valve during a flushing action. 75

3. A flush-valve having a supply-chamber, a discharge-chamber beneath the same and a compression-chamber intermediate to the supply and discharge-chambers, a diaphragm separating said compression and discharge chambers, a relief-valve-box attached 80 to the diaphragm with an air-sniffer-pipe extended upwardly therefrom in the compression-chamber, and a valve-stem extended through the diaphragm with a relief-valve inside the relief-valve-box, whereby air in 85 the upper part of the compression-chamber is discharged every time the relief-valve is opened. 90

4. A flush-valve having a discharge-chamber and a compression-chamber at one side 95 of the same with a diaphragm separating the two, a relief-valve-box in the compression-chamber with a relief-valve having its stem extended through the diaphragm and shifted by the movement of the flushing-spindle, the relief-valve-stem having a passage for venting 100 the compression-chamber, a circular diaphragm-seat adjacent to the outer side of the diaphragm, and a flushing-spindle having a sleeve-valve fitted within said circular seat 105 and movable toward the diaphragm to prevent the flushing except when desired.

5. A flush-valve comprising a discharge chamber, a compression chamber, a diaphragm separating said chambers, a flushing 110 spindle, a relief valve for effecting a reduction in pressure within said compression chamber and having a stem extending through said diaphragm and shiftable by a movement of said spindle, and a relief valve 115 box supported by said diaphragm and disposed within said compression chamber, said box having means extending into said compression chamber to such a position as to permit escape of the air therein. 120

6. A flush valve having a casing with a discharge chamber and a compression chamber, a diaphragm separating the said chambers, a relief valve box attached to the diaphragm with a relief valve having a stem 125 projecting into the discharge chamber and formed to provide a passage, means communicating with said compression chamber and said passage to vent the compression chamber, the valve casing having a flush 130

valve spindle fitted movably with respect thereto to engage said stem for actuating the relief valve, and means for preventing leakage between said spindle and said 5 casing.

7. A flush-valve having a supply-chamber and discharge-chamber with a compression-chamber intermediate the same, with its casing secured detachably upon the outer 10 side of the supply-chamber, a diaphragm separating the said chambers, a relief-valve-box attached to the diaphragm within the compression-chamber and having an air-sniffer-pipe extended upwardly, and means 15 within the compression-chamber to locate the air-pipe at the top of the compression-chamber.

8. A flush-valve comprising a supply chamber having an inlet opening, a discharge 20 chamber, a compression chamber, an annular valve seat, a valve normally resting upon said seat and disposed between said compression chamber and said discharge chamber, and an equalizing port comprising 25 a direct passage extended through said valve, said port being disposed externally to said valve seat and adjacent said inlet opening and having the end thereof disposed in the path of movement of fluid from the coming 30 through said inlet opening during a flushing action of the valve.

9. A flush valve having a discharge chamber and a compression chamber, a diaphragm separating said chambers, a supply chamber, 35 a nipple projecting from said diaphragm for the entrance of fluid into said compression chamber, the free end of said nipple being disposed in the path of flow of fluid from the supply chamber to the discharge chamber, 40 and means for removing air from said compression chamber.

10. A flush valve having a discharge chamber and a compression chamber, a diaphragm separating said chambers, and means for permitting a removal of air from 45 said compression chamber prior to the outlet of liquid therefrom.

11. A flush valve having a discharge chamber and a compression chamber, a diaphragm separating said chambers, a conductor extending through liquid in said compression chamber to afford an outlet for air in said compression chamber in predetermined relation to the outlet of liquid from 55 said compression chamber.

12. A flush valve having a discharge chamber and a compression chamber, a diaphragm separating said chambers, a conductor extending through liquid in said compression chamber to afford an outlet for air in said compression chamber prior to the outlet of liquid from said compression chamber.

13. A flush valve comprising a fluid supply chamber, a compression chamber, a dis-

charge chamber, a diaphragm separating said compression and discharge chambers, a relief valve permitting the passage of fluid from said compression chamber to said discharge chamber for a flushing operation, and means for releasing trapped air to effect a substantial noiseless flushing operation. 70

14. A flush valve comprising a fluid supply chamber, a compression chamber, a discharge chamber, a diaphragm separating said compression and discharge chambers, a relief valve for permitting the passage of fluid from said compression chamber to said discharge chamber for a flushing operation, and a conduit for the outlet of air from said compression chamber to effect a substantially silent flushing operation. 75

15. A flush-valve comprising a supply chamber, a discharge chamber, a compression chamber, an annular valve seat, a valve normally resting upon said seat and separating said chambers from one another, a relief valve supported by said valve, means for operating said relief valve to produce a flushing action, and means adapted to be interposed between said valve and its seat for preventing such flushing action occurring until the operating means returns to initial position. 80

16. A flush-valve comprising a supply chamber, a discharge chamber, a compression chamber, an annular valve seat positioned between said chambers, a valve normally resting upon said seat and separating said chambers from one another, means for effecting a change in pressure in said compression chamber, said means adapted to be interposed between said valve and its seat including an operating spindle, and means for preventing a flushing action in the event said spindle becomes jammed. 90

17. A flush-valve comprising a supply chamber, a discharge chamber, a compression chamber, an annular valve seat positioned between said chambers, a valve normally resting upon said seat and separating said chambers from one another, a relief valve for effecting a change in pressure within said compression chamber, means for operating said relief valve including an operating handle, and means adapted to be interposed between said valve and its seat for preventing the water in said supply chamber from passing into said valve in the event said operating handle is held out of its normal position. 110

18. A flush-valve comprising a supply chamber, a discharge chamber, a compression chamber, a tubular member forming a passageway from said supply chamber to said discharge chamber, a diaphragm normally resting upon one end of said tubular member to prevent a flow of water from said supply chamber to said discharge chamber and serving to separate the compression 115 120 125 130

chamber and supply chamber, a relief valve carried by said diaphragm, a sleeve valve slidible within said tubular member, and means for operating said relief valve and 5 said sleeve valve, said sleeve valve adapted to engage said diaphragm and prevent the water from said supply chamber entering said tubular member until said sleeve valve is withdrawn from engagement with said diaphragm. In testimony whereof I have hereunto set my hand.

EDWARD G. HEDGES.
